IMAGE ELIMINATION RECEIVER

Murray G. Crosby, Riverhead, N. Y., assignor to
Radio Corporation of America, a corporation
of Delaware

Application July 15, 1937, Serial No. 153,754

20 Claims. (Cl. 250—20)

This invention concerns an image elimination scheme to be used in the reception of amplitude or phase or frequency modulated wave energy. In this scheme the phase modulation component, inherently resulting from the combination of the carrier and local oscillator, is converted by novel means into corresponding amplitude modulation components which are combined with the inherently resulting amplitude modulation component of the combination so that the two types of modulation inherently produced and superposed on the signal modulation oppose and cancel on one side of zero beat and aid on the other side. The receiver is tuned so that the desired signal is on the side of the zero beat where the components aid. This converting system acts as the heterodyne detector of the receiver so that the wave at the output thereof from which the image frequency has been compensated or suppressed may be impressed on a frequency or phase or amplitude modulation wave demodulator.

In a modification, this novel converting means which suppresses the image frequency by opposing components of the same on one side of the carrier also reproduces the useful signal modulation which can be used directly from the output of the converter.

In the prior art of image reduction in superheterodyne receivers the reduction has been accomplished by means of selectivity. The first intermediate frequency is generally made as high as possible so that the radio frequency selectivity will eliminate unwanted signals which are twice the intermediate frequency away from the desired signal. However, high intermediate frequencies are undesirable because they cannot be made as selective as the low ones. Consequently, two intermediate frequencies are used on the more selective receivers so that both image reduction and selectivity may be obtained.

The arrangement disclosed in this invention is similar in some respects to that of Hansell United States Patent #2,044,745 dated June 16, 1936 wherein a balance is obtained which eliminates the image signal. However, this arrangement applies different principles to produce the balance.

In describing my invention reference will be made to the attached drawings wherein,

Figures 1, 2, and 4 illustrate by circuit diagrams different embodiments of modulated wave energy receivers which include the novel image suppression means described above and are arranged in accordance with my invention. In Figure 4 a heterodyne receiver of the zero beat frequency type is used whereas separate oscillators are used in the other circuits;

Figures 3a to 3h illustrate graphically the manner in which the inherent amplitude modulations and phase modulations of the wave due to the

local oscillator are related and combined to suppress image frequencies, i. e., frequencies on one side of the carrier, and leave desired frequencies;

Figure 5 illustrates a modified form of receiver wherein a phase modulation detector is used to demodulate the phase modulation component, the amplitude modulation component being limited off; while

Figures 6, 7, 8, and 9 are graphs or curves illustrating the operation of the several circuits or elements thereof.

The vector diagrams of Figures 3a to 3h give a vector representation of the relation between the incoming signal and the local oscillator voltage of a superheterodyne receiver. Thus, E₁ represents the local oscillator voltage, E₂ the incoming signal voltage, and E_r the resultant voltage, formed by the combination of these two first voltages. The different representations 3a, 3b, 3c, etc., show successive instances of time. The counter-clockwise direction of rotation is taken as the positive direction; hence as voltage vector E₂ rotates counter-clockwise about voltage vector E₁, voltage E₂ must be higher in frequency than voltage E₁. By viewing the diagrams in the sequence 3a, 3b, 3c, 3d, 3e, 3f, 3g, 3h, voltage vector E₂ appears to be the higher frequency and by viewing in the sequence 3a, 3h, 3g, 3f, 3e, 3d, 3c, 3b, vector E₂ appears to be the lower frequency.

From the diagrams of Figures 3a to 3h, it can be seen that the resultant of the two voltages

is modulated in amplitude between the limits given by diagrams 3c and 3g and in phase between the limits given by diagrams 3a and 3e. Thus,

there are two types of modulation present. Ordinarily only the amplitude modulation component is detected to obtain the heterodyne signal, the phase modulation component being disregarded. However, in this invention both of the

modulations present are received and combined so that the image, or the signal which is on the other side of zero beat with the local oscillations, is cancelled out. Careful examination of the

vector diagrams in the sequence 3a, 3b, 3c, 3d, 3e, 3f, 3g, 3h, and then in the sequence 3a, 3h, 3g, 3b, 3c, etc., will disclose that the phase of the amplitude envelope is 180° apart for the two sequences.

However, the phase deviations are in-phase for the two sequences. Thus, if the detected amplitude modulation were combined with the detected phase modulation the two buck on one side of zero beat and aid on the other side. This

effects an image elimination. On the other hand there is another point to be considered; that is the fact that the detected phase modulation inherently has a 90° phase shift with respect to the amplitude modulation. To correct for this

shift a phase shifter may be placed in a circuit through which the detected phase modulation

50

85

90

95

passes before it is combined with the amplitude modulation. Such a receiver would be similar to the receiver of Hansell United States Patent #2,044,745.

5 The method used in this invention to combine the two types of modulation is to receive the phase modulation on a frequency modulation receiver. Frequency modulation is the rate of change of phase modulation. The rate of change of the 10 phase is 90° displaced from the actual value of the phase. That is when the phase deviation is at its maximum value the frequency deviation is at its minimum value. Thus, such reception inherently applies another 90° phase shift to the 15 detected phase modulation without the insertion of a phase shifter and the circuit is simplified. Thus, in my novel system the phase modulation portion of the resultant is received on a frequency modulation receiver circuit and the amplitude 20 modulation portion of the resultant is received on an amplitude modulation receiver circuit. The two resultants are then combined at proper amplitude so that the outputs of the two circuits aid for the desired signal on one side of the local oscillator frequency and buck for the undesired signal or image on the other side of the local oscillator frequency.

Figure 1 shows one type of circuit that may be used. The frequency modulation receiver circuit 30 is of the retard circuit pentode detector type described in Crosby United States applications #618,154 filed June 20, 1932, and #25,231 filed June 6, 1935. Tube 1 is a combining tube, 2 the local oscillator and 3 and 4 pentode detectors. 35 The amplitude or phase or frequency modulated wave which is to be demodulated with image suppression is impressed by a line connected with any source such as a wave repeater or an amplifier or an aerial on a circuit 5 tuned to the mean 40 frequency of said wave and from 5 to control grids 12 and 14 of tubes 1 and 4. The oscillations produced in 2 of a frequency determined by the constants of 8 are supplied by coupling condenser 11 to pentode electrodes 16 and 18 of tubes 1 and 45 4 respectively. The anode of tube 1 is coupled by coupling condenser 10 directly to the grid electrode 20 of tube 3 and by the coupling and phase retarding circuit 6 to the pentode electrode 22 of tube 3. The anodes 24 and 26 of tubes 3 and 4 are coupled in phase opposition by the primary 50 winding of a transformer 7. The secondary winding of 7 may be coupled to any type of output circuit, such as an audio frequency output or a low intermediate frequency output. If the output 55 at 7 is of intermediate frequency a phase or frequency or amplitude modulated wave demodulating means may be coupled to 7, depending on the nature of the wave modulation at 5. If the wave impressed on 5 is continuous the beat frequency 60 will appear in 7.

The signal to be heterodyned is fed to tuned circuit 5 and to the grid of tube 1 where it is combined with the oscillations from circuit 8. The 65 combined voltage is fed from 1 to transformer or retard circuit 6 and thence to the suppressor 22 of pentode detector 3. The unretarded combined voltage is fed directly from the plate circuit of the combining tube 1 by means of coupling condenser 10 to the control grid 20 of tube 3. Thus, pentode detector 3 has retarded voltage 70 fed to one grid, 22, and unretarded voltage fed to the other grid, 20, and the detected frequency or phase modulation will appear in its plate circuit. If we call the time delay of the wave pro-

duced in circuit 6 "D" the phase of the output of this circuit would be:

$$\alpha = 2\pi \frac{D}{T} \quad (1)$$

where T is the period of the wave applied and α is 5 in radians.

This may be rewritten:

$$\alpha = 2\pi Dt \quad (2)$$

$$\alpha = 2\pi 1f/V \quad (2a) \quad 10$$

where f is the frequency of the applied wave, 1 is the electrical length of the retard circuit 6, and $V=3X 10^8$ meters per second.

Thus, the phase of the output of the retard circuit 6 is directly proportional to the applied 15 frequency. In the case of a frequency modulated wave given by:

$$e = E \cos (wt - fd/fm \cos pt) \quad (3)$$

where $w=2\pi \times$ carrier frequency, fd =frequency 20 deviation with modulation and $p=2\pi fm$, where fm =the modulating frequency, the instantaneous frequency is given by

$$\frac{d(wt - fd/fm \cos pt)}{dt} = 2\pi (fc + fd \sin pt) \quad (4) \quad 25$$

$$t = (fc + fd \sin pt) \quad (5)$$

Substituting (5) in (2) gives:

$$\alpha = 2\pi D(fc + fd \sin pt) \quad (6)$$

Hence, the wave passed through the retardation 30 circuit has the phase given by (6) added to it, or

$$e = E \cos \{wt - fd/fm \cos pt + 2\pi D(fc + fd \sin pt)\} \quad (7)$$

The grids of the detector 3 are adjusted according to the characteristics of Figures 6 and 7. 35 Both grids are adjusted to point "a" which is the linear portion of the characteristic. Thus, in accordance with the general detailed description of this detector given in my United States application Serial #716,469 filed March 20, 1934, Patent #2,063,588 dated December 8, 1936, the variable current in the output of the detector would 40 be substantially given by:

$$J = a_1 a_2 e_1 e_2 \quad (8) \quad 45$$

where a_1 and a_2 are constants of the tube and e_1 and e_2 are the two grid voltages. Applying the unretarded voltage of Equation (3) to one grid, say 20, and the retarded voltage of (7) to the other grid, say 22, gives as the variable output: 50

$$J = a_1 a_2 E_1 \cos (wt - fd/fm \cos pt) \times E_2 \cos \{wt - fd/fm \cos pt + 2\pi D(fc + fd \sin pt)\} \quad (9)$$

simplifying and eliminating radio frequency 55 terms which would be eliminated by the low pass filter in the detector output, the variable output would be:

$$J = \frac{a_1 a_2 E_1 E_2}{2} \{ \cos 2\pi Dfc \cos 2\pi Dfd \sin pt - \sin 2\pi Dfc \sin 2\pi Dfd \sin pt \} \quad (10) \quad 60$$

In practice, $2\pi Dfc$ is adjusted to equal $\pi/2$, $3\pi/2$, $5\pi/2$, etc., so that

$$J = \frac{a_1 a_2 E_1 E_2}{2} \sin 2\pi Dfd \sin pt \quad (11) \quad 65$$

by applying the Bessel Function Expansion:

$$\sin (X \sin \phi) =$$

$$2J_1(X) \sin \phi + 2J_3(X) \sin 3\phi + \dots \quad (12) \quad 70$$

the following is obtained:

$$J = \frac{a_1 a_2 E_1 E_2}{2} [J_1(2\pi Dfd) \sin pt + J_3(2\pi Dfd) \sin pt + \dots] \quad (13)$$

Thus, the output of the detector 3 consists of 75

the fundamental frequency $\sin pt$ proportional to a first order Bessel function of $2\pi Dfd$ and all the odd harmonics of the modulation frequency. The second harmonic, which normally is present in square-law detection, is absent from the output of this detector. The phase modulations on the wave received consisting of the combination of the local oscillator and the incoming wave has been demodulated and appear in the output circuit 7 of detector 3. This method of demodulation has been described in Crosby application #25,231 filed June 6, 1935, Patent No. 2,087,429, July 20, 1937.

The amplitude modulation component of the resultant of the local oscillator and signal is detected by means of pentode detector tube 4. Oscillations from local oscillator 2 is fed to one grid 18 and the signal to the other grid 14 and the detected amplitude modulation appears in the plate circuit in the conventional manner known to the art. Thus, the detected amplitude component and the frequency detected phase component obtained as described above are combined in transformer 7 and the heterodyne output is taken from the secondary of this transformer. Moreover, as pointed out in detail hereinbefore, the components inherently produced by amplitude modulation of the signal wave and phase modulation of the signal wave by the oscillations from oscillator 2 buck out on one side of zero beat and add on the other side of zero beat to produce the signal and eliminate image frequencies. This operation will be clear when one keeps in mind the fact that as indicated in Figures 3a to 3h the polarity of the envelope of the amplitude modulation component is opposite on both sides of zero beat whereas the envelopes of the phase modulation component are the same on both sides of zero beat.

In the circuit of Figure 2, the sloping filter type of frequency modulation receiver is employed. The wave energy is fed from circuit 4 to grids 12 and 14. Oscillations are fed from oscillator 2 to the control grid 34 of amplifier and coupling tube 9 and to the pentode electrode 18 of detector 4. The output of tube 1 is beat with the output of tube 9 and the energy of intermediate frequency is impressed on a filter 6' having a sloping characteristic as illustrated in Figure 8. This filter converts the phase or frequency modulations on the wave into amplitude changes which are impressed on the control grid 20 of detector 3. The output of detector 3 contains modulation components characteristic of signal modulation by the combination of oscillations from oscillator 2 and coupling tube 9 and the signal wave.

The wave energy is also impressed from circuit 5 on grid 14 of tube 4 and from oscillator tube 2 and tuned circuit 8 through coupling condenser 11 to the electrode 18 of tube 4 so that the inherent amplitude modulations by the local oscillator 2 are detected in tube 4 as in Figure 1. Separate combining tubes 1 and 9 combine the local oscillations from oscillator and circuit 2 and 8 and the signal from circuit 5 so that their resultant appears in the common plate circuits including filter 6' of the combining tubes 1 and 9. This resultant is fed through sloping filter 6' and thence to the control grid 20 of detector 3 to detect the phase modulation component resulting from beating local oscillations from tube 2 with the received wave from circuit 5. Pentode detector tube 4 detects the amplitude component in the same manner as in the circuit of Figure 1.

The two energies resulting from detecting these components are combined so that signals on one side of the local oscillator add and those on the other side thereof buck and compensate or neutralize. If wave energies on one side of the local oscillator add they must oppose on the other side of the local oscillator. The output of coupling transformer 7 which is free of image frequencies may be impressed on any utilization circuit such as an intermediate frequency amplifier or an audio frequency amplifier for beat note reception.

In the above circuits the manner in which element voltages are applied has been omitted for simplicity inasmuch as their placement and values will be obvious to one versed in the art from the illustration thereof. Automatic volume control circuits may be added in conventional manners in order to adjust the balance and the operating levels.

The operation of the above circuits is not confined to any frequency. Thus, the principle may be applied to a first or second detector of a superheterodyne or may be applied to an autodyne or non-superheterodyne receiver. Figure 4 shows the principle applied to an autodyne receiver. Autodyne amplifier tube 36 with its input circuit 5 and regeneration circuit 38 supplies the combination of local oscillations and signal to be detected as amplitude modulation in detector tube 4 and as phase or frequency modulation in frequency modulation detector 3. The phase modulation component is demodulated by passing the combined signal and oscillator voltage through coupling or limiter tube 48 and converting to amplitude modulation by means of the side of the resonance of tuned circuit 6'' which has a characteristic as shown in Figure 8. Tuned circuit 6'' may be replaced by any type of sloping filter such as shown at 6' in Figure 2. If tube 40 is a limiter tube it helps to remove the amplitude modulation component so that detector tube 3 produces an output purely dependent upon the phase modulation component of the resultant voltage. However, such limiting is not strictly necessary since the amplitude component appearing in the output of detector 3 may be balanced out by energy of opposite phase from the amplitude modulation component supplied by detector tube 4. The outputs of the two detectors are combined in proper phase, as determined by switch 30, so as to add the components on a selected side of the local oscillations and oppose on the other side of the local oscillations to balance the image signal. Adjustment of the balance could be made by varying tuned circuit 6'' or by varying a volume control in a circuit supplying voltages to an element of tube 40, such as control grid 42.

By eliminating tube 4 of Figure 4 and utilizing the output of detector tube 3 only, a novel form of detection would be available which would have distinct advantages. This type of detection would be the detection of the phase modulation component of the resultant of the combined local oscillator and signal voltages. Ordinarily only the amplitude modulation component is detected. However, this receiver would limit off the amplitude modulation component and receive the phase modulation component as frequency modulation. Such a detection makes the heterodyne output proportional to its frequency. Hence, as the heterodyne note is made closer to zero frequency its output will be decreased towards zero. This enables the elimination of certain interfering signals by tuning the heterodyne note of the de-

sired signal so that the interfering signal is heterodyned to zero or near zero frequency.

Another novel form of detection in place of the conventional amplitude modulation detection involves the employment of phase modulation detection principles to detect the phase modulation component of the resultant. The circuit of Figure 5 shows an arrangement which will do this. The signal is fed into tuned circuit 5 and is combined with energy from local oscillator 2 in combining tube 1. Tuned circuit 6'', tuned to the frequency of circuits 8 and 5 passes the combined energy on to limiter tube 40 which has low element voltages to cause limiting. The limiter 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 tion component present on the resultant in circuit 42.

In the apparatus of Figure 5, tube 40 is a limiter. Consequently, it will remove the amplitude modulation component of the combination of the local oscillator 2 and the incoming signal. This will leave the phase modulation of the resultant as the only modulation left for the purpose of detecting the beat between the local oscillator and the incoming signal. Since phase modulation cannot be detected by the ordinary nonlinear device, a detector 44 of the multigrid type is employed and the phase modulated signal is applied to G₁ while the local oscillator is fed to G₂. This type of detection detects the phase modulations of the resultant just as if the phase modulation were converted to amplitude modulation first and detection then accomplished on a nonlinear device. The above mathematics which result in Equation (25) show the output of such a detector when a wave is applied at its input which is both amplitude and phase modulated. Due to the action of the limiter tube 40, the amplitude modulation component will be removed making "m"=zero. The resultant output will then be given by:

$$i_{a.c.} = \frac{a_1 a_2 E_1 E_2}{2} \{ 2 J_1(\phi) \sin qt + 2 J_3(\phi) \sin 3qt + \dots \} \quad (26)$$

In Equation (26), ϕ would represent the degree of phase modulation caused by the combination of the incoming signal with the local oscillator and "q" would represent the angular velocity of the difference frequency resulting between the incoming signal and the local oscillator. Thus, the output of the detector consists of a frequency which is equal to the difference between the local oscillator frequency and the incoming signal frequency. This frequency is the desired beat frequency and is the same frequency that would be obtained if the incoming signal and the local oscillator were combined and detected for the amplitude modulation present on their resultant in the conventional manner.

In any of the above described circuits the wave may be frequency multiplied at any point where the modulation present is substantially phase modulation. This would increase the phase deviation of the resultant of the incoming wave and the local oscillator. For instance, in the circuit of Figure 1, retard circuit 6 might be tuned to twice the frequency of the incoming signal so as to make tube 1 a frequency multiplier. In Figure 5, circuit 6' could be tuned in the same manner so as to make tubes 1 and 9 frequency multipliers. In Figures 4 and 5, tuned circuits 6'' and 42 may also be tuned to a harmonic to make tubes 40 frequency multipliers. This application of frequency multiplication would increase the sensitivity of the detecting system. Limiting might also be accomplished in amplifier tube 1 of Figures 1 and 2 as well as in coupling tubes 40 of Figures 4 and 5.

I claim:

1. The method of suppressing the effects of an undesired band of frequencies which includes the steps of, receiving signal energy including said undesired band of frequencies, generating local oscillatory energy, beating the undesired band of frequencies with the locally generated energy to produce resultant energy having phase modulation and amplitude modulation components thereon resulting from said beating action, detecting said components and simultaneously pro-

ducing relative phase displacement in the detected energies and combining the detected energies to balance out the beat frequencies characteristic of said undesired band of frequencies.

2. The method of suppressing the effects of an undesired band of frequencies which includes the steps of, receiving signal energy including said undesired band of frequencies, generating local oscillatory energy of a frequency different than the frequency of said signal energy, beating the undesired band of frequencies with the locally generated energy of different frequency to produce beat frequencies having phase modulation and amplitude modulation components thereon resulting from said beating action, detecting said components and simultaneously producing relative phase displacement in the detected energies and combining the resultant energy to balance out the beat frequencies characteristic of said undesired band of frequencies.

3. The method of suppressing the effects of undesired bands of frequencies on receivers of the heterodyne type which includes the steps of receiving signal energy including said undesired band of frequencies, generating local energy, beating the undesired bands of frequencies with the locally generated energy to produce beat frequencies having phase modulation and amplitude modulation components thereon resulting from said beating action, separately detecting said components and simultaneously producing relative phase displacement between the detected components and directly combining the resultant energy to balance out the beat frequencies characteristic of said undesired band of frequencies.

4. The method of receiving desired bands of frequencies and excluding undesired bands of frequencies which includes the steps of receiving all of said bands of frequencies, generating local oscillatory energy differing from said received energy by a beat frequency, beating said local oscillatory energy with all of said received energies to produce a beat note modulated in phase and amplitude in accordance with said undesired frequencies, demodulating the phase modulated component of said beat note, and simultaneously producing a phase shift in the demodulation component, demodulating the amplitude modulation component of said beat note, and combining the demodulated energies whereby the energies characteristic of the undesired bands oppose and the energies characteristic of the desired bands add.

5. The method of receiving desired bands of frequencies and excluding undesired bands of frequencies which includes the steps of receiving all of said bands of frequencies, generating local oscillatory energy differing from said received energy by a beat frequency, beating said local oscillatory energy with all of said received energies to produce a beat note energy modulated in phase and amplitude in accordance with said undesired frequencies, demodulating the phase modulated component of said energy and simultaneously producing a phase shift in the demodulated energy relative to the original phase modulations on the energies, demodulating the amplitude modulation of said energy, and combining the demodulated energies whereby the energies characteristic of the undesired bands oppose and the energies characteristic of the desired bands add.

6. The method of demodulating desired signal carrying wave energy and undesired signal modulated wave energies of different frequencies and

eliminating from the output demodulation components characteristic of the undesired wave energies which includes the steps of, receiving all of said wave energies, generating local oscillations differing from said received wave energies by a beat frequency, combining all of said wave energies with said locally generated oscillations to produce energy of beat frequency which is modulated in phase and in amplitude by said 10 combining action, separately demodulating the phase modulation components on said energy of beat frequency and simultaneously producing a phase shift in the demodulated energy relative to the phase modulations on said energy of beat 15 frequency, demodulating energy characteristic of the amplitude modulations on said energy of beat frequency, and combining said last demodulated energy with said first demodulated energy whereby the demodulated energies on one side of 20 zero beat frequency adds and the demodulated energies on the other side of zero beat frequency oppose and cancel.

7. In a system for receiving wave energy modulated at signal frequency and undesired wave 25 energy and for demodulating the same and removing the effects of the received undesired wave energy on the modulated output including, wave receiving means of the heterodyne type, a utilization circuit, a frequency modulated wave de- 30 modulating means connecting said first means to said utilization circuit and amplitude modulated wave demodulating means of the heterodyne type coupling said first means to said utilization circuit.

35 8. In a system for demodulating wave energy and suppressing image frequencies caused by received undesired wave energy, a combining tube having input electrodes excited by all of said wave energies, said combining tube having output electrodes, a source of oscillations of a frequency different than the frequency of said received wave energy, means for impressing oscillations from said source on said combining tube to beat with said received wave energy, a first electron discharge tube having input and output electrodes, a frequency discriminating circuit connecting the input electrodes of said first electron discharge tube to the output electrodes of said combining tube, a second electron discharge tube having input and output electrodes, a circuit coupling the input electrodes of said second discharge tube to said source of oscillations, means for impressing said wave energies on said last input electrodes, and a common circuit connected 55 with the output electrodes of said first and second discharge tube.

9. In a system for demodulating wave energy and suppressing image frequencies caused by received undesired wave energy, a combining 60 tube having input electrodes excited by all of said wave energies, said combining tube having output electrodes, a source of oscillations of a frequency different than the frequency of said received wave energy, tube means for impressing 65 oscillations from said source on said combining tube to beat with said received wave energy, a first electron discharge tube having input and output electrodes, a frequency discriminating circuit connecting the input electrodes of said first electron discharge tube to the output electrodes of said combining tube, a second electron discharge tube having electrodes excited by said wave energy, said tube having output electrodes, tube means coupling the input electrodes of said second electron discharge tube to said oscillator,

and a common circuit connected with the output electrodes of said first and second discharge tube.

10. In a system for demodulating wave energy and suppressing image frequencies caused by received undesired wave energy, an oscillating 5 combining tube having input electrodes excited by all of said wave energies, said combining tube having output electrodes, means for impressing said wave energies on said oscillating combining tube to produce beat energy, a first electron discharge tube having input and output electrodes, a frequency discriminating circuit connecting the input electrodes of said first electron discharge tube to the output electrodes of said oscillating combining tube, a second electron discharge tube having input and output electrodes, a circuit coupling the input electrodes of said second discharge tube to said oscillating combining tube, and a common circuit connected with the output electrodes of said first and second discharge tube. 20

11. A system as recited in claim 8 including means for tuning said frequency discriminating circuit to a harmonic of the frequency of the wave energies, and means for causing said combining tube to act as a frequency multiplier. 25

12. A system as recited in claim 9 including means for tuning said frequency discriminating circuit to a frequency which is a harmonic of said wave energy.

13. A system as recited in claim 10 including means for tuning said frequency discriminating circuit to a harmonic of said wave energy. 30

14. The method of demodulating wave energy modulated in phase, frequency, or amplitude and for eliminating from the resultant energy image frequencies caused by undesired wave energy of a frequency adjacent to the frequency of the desired wave energy which includes the steps of, beating all of said wave energy with locally generated oscillations differing from said wave 40 energies by an intermediate frequency, said beating action producing intermediate frequency energy modulated in phase and in amplitude due to the combination of the wave energies with said locally generated oscillations, demodulating 45 the phase modulations on said intermediate frequency energy, demodulating the amplitude modulations on said intermediate frequency energy, and combining the resultant energies whereby the modulation components on one side of zero beat frequency add and those on the other side oppose. 50

15. The method of demodulating wave energy modulated in phase, frequency, or amplitude and for eliminating from the resultant energy image 55 frequencies caused by undesired wave energy of a frequency adjacent to the frequency of the desired wave energy which includes the steps of, beating all of said wave energy with locally generated oscillations differing from said wave 60 energies by an intermediate frequency, said beating action producing an intermediate frequency energy modulated in phase and in amplitude due to the combination of said wave energies with said locally generated oscillations, demodulating 65 the phase modulations on said intermediate frequency energy and simultaneously producing a 90° phase shift in the demodulated energy relative to the phase modulations on said intermediate frequency energy, demodulating the amplitude modulations on said intermediate frequency energy, and combining the resultant energies whereby the modulations resulting from the desired wave energy add and the modulations 70

resulting from the undesired wave energy oppose and cancel.

16. The method of demodulating modulated wave energy which includes the steps of, combining said modulated energy with locally generated oscillations to produce resultant energy, limiting and frequency multiplying the resultant energy, and detecting the phase deviations produced on said resultant by said combination to produce signal carrying energy of a frequency equal to the difference between the frequency of said locally generated oscillations and the mean frequency of said modulated energy.

17. The method of demodulating modulated wave energy which includes the steps of, combining said modulated wave energy with locally generated oscillations to produce resultant energy the phase of which varies due to said combination, limiting and frequency multiplying said resultant energy, and detecting the effective frequency variations of the said phase variations of the resultant energy.

18. The method of demodulating modulated wave energy which includes the steps of, combining said modulated wave energy with locally generated oscillations to produce resultant energy varying in phase due to said combination, limiting and frequency multiplying the resultant energy, detecting said phase variations on said resultant energy to produce energy of a frequency equal to the difference between the frequency of said locally generated oscillations and

the mean frequency of said modulated energy, and demodulating said energy of difference frequency to reproduce the signal.

19. The method of demodulating modulated wave energy which includes the steps of, combining said modulated energy with locally generated oscillations to produce resultant energy varying in amplitude and in phase, limiting the resultant energy to substantially remove said variations in amplitude, and detecting the phase deviations produced on said resultant by said combination to produce signal carrying energy of a frequency equal to the difference between the frequency of said locally generated oscillations and the mean frequency of said modulated energy.

20. The method of demodulating modulated wave energy which includes the steps of, combining said modulated wave energy with locally generated oscillations to produce resultant energy varying in amplitude and in phase due to said combination, limiting the resultant energy to substantially remove therefrom the said variations in amplitude, detecting said phase variations on said limited resultant energy to produce energy of a frequency equal to the difference between the frequency of said locally generated oscillations and the mean frequency of said modulated energy, and demodulating said energy of difference frequency to reproduce the signal.
